UNITED STATES PATENT OFFICE

2,034,398

HANDBAG

Benjamin Kash, Los Angeles, Calif.

Application May 3, 1935, Serial No. 19,645

4 Claims. (Cl. 150—34)

This invention relates to ladies' hand bags, pocket-books, purses, pouches, vanity cases, and the like.

The general object of the invention is to provide a lady's hand bag or pocket-book constructed with a dispenser for dispensing cigarettes, chewing gum, candy, or other articles.

A more particular object is to provide a lady's hand bag or pocket-book with a dispenser which is operated by an ornamental button on the front side of the bag, and which partly ejects its articles through one end of the bag, so that the article may be grasped and pulled completely out of the dispenser and bag, or pushed back into the dispenser, if desired, the discharge opening for the dispenser in the end of the bag being normally covered and hidden by a flap which is engaged and swung up to uncover said opening by each article as it is dispensed.

20 A further object is to provide a dispenser of the character stated which is compact and light, so that it will occupy only a small space in the hand bag or pocket-book and will add no appreciable weight thereto.

25 Other objects and advantages of the invention will appear as this specification progresses.

With the above and other objects in view, the invention consists in the novel and useful provision, formation, construction, association, and relative arrangement of parts, members and features, all as disclosed in a certain embodiment in the accompanying drawing, described generally, and more particularly pointed out in the claims.

In the drawing:

35 Figure 1 is a perspective of a lady's hand bag embodying my invention, showing the front of the bag and the end thereof through which articles are dispensed, and showing the dispenser operating button in its normal position and the flap of the dispenser discharge opening in position covering said opening;

40 Figure 2 is a fragmentary perspective like Figure 1, except that the dispenser operating button is shown turned to operate the dispenser and a cigarette is shown partly ejected from the dispenser through its discharge opening in one end of the hand bag, and the flap for said opening is shown swung away from said discharge opening by said cigarette, allowing the cigarette to be dispensed,

45 Figure 3 is a perspective of said hand bag with its closing flap swung open and showing the interior of the hand bag;

50 Figure 4 is a transverse vertical section of this hand bag taken on line 4—4 of Figure 1,

Figure 5 is a fragmentary vertical longitudinal section of the bag taken on line 5—5 of Figure 4,

Figure 6 is a horizontal section of the dispenser casing taken on line 6—6 of Figure 5,

Figure 7 is a transverse vertical section of the 5 dispenser casing taken on line 7—7 of Figure 5,

Figure 8 is a fragmentary vertical section taken on line 8—8 of Figure 1, and,

Figure 9 is a fragmentary horizontal section taken on line 9—9 of Figure 1.

Referring with particularity to the drawing, 10 designates a lady's hand bag including a front wall 2, rear wall 3; bottom wall 4, accordion foldable end walls 5 and 6; closing flap 7 extending from the upper edge of the rear wall 3 over the 15 top of the bag and downwardly over the front wall of the bag; a large pocket 8 on the inside of the rear wall 3 of the bag, which is closed by a zipper fastener 9; a smaller pocket 10 for a mirror on the inside of the front wall 2; and a small 20 pocket 11 on the outside of the rear wall 3 for small articles, such as a package of matches.

I provide a pocket 12 on the inside of the front wall 2 of the bag for my dispenser 13, which pocket is closed at the top by a flap 14 secured 25 at its upper edge to the inside of the front wall 2 at the upper edge of said wall, as at 15, the lower edge of said flap extending downwardly over the upper edge of said pocket and being detachably connected to said pocket by a snap button 16. 30

35 My dispenser 13 comprises primarily a magazine 17, an ejector 18 and ejector-operating mechanism 19, which magazine, ejector and most of said ejector mechanism are confined within a casing 20. Said casing is formed in three parts, 35 a front vertical member 21, a rear vertical member 22, and a cover 23. The front member 21 is formed with a front wall 24, vertical side walls 25 and 26; and a lower horizontal wall 27. The rear member 22 is formed with a rear wall 28, 40 vertical side walls 29 and 30 and a lower horizontal wall 31. The rear member 22 fits over the front member 21, the side walls 29 and 30 and lower wall 31 of the rear member telescoping over the side walls 25 and 26 and the lower wall 45 27 respectively of the front member. The cover 23 is trough shaped and telescopes over the top of said front member 21 and rear member 22 holding said members together at the top. A vertical partition 32 is provided in the front member 21 extending downwardly from a horizontal flange 33 extending inwardly from the upper edge of the front wall 24 of said front member, said partition dividing the casing 20 into the magazine 17 and a compartment 34 for the ejector op- 50 55

erating mechanism 19, and the lower end of said partition being spaced a short distance above the lower wall 21 of the front casing member 21 to provide an opening 35 through which the ejector 18 passes during its operation, in the manner hereinafter described. The end wall 29 of the casing member 22 rests adjacent the inside of the end wall 5 of the hand bag and the casing 20 is provided with a discharge opening 36 leading from the bottom of the magazine 17 through the end of the casing which lies adjacent the end wall 5 of the hand bag, the end walls 25 and 29 of the casing members 21 and 22 being cut away to provide such opening. The discharge opening 36 of the magazine 17 registers with an outlet 37 in the lower part of the end wall 5 of the hand bag. The lower wall 27 of the casing member 20 is extended through the outlet 37 in the end wall 5 of the hand bag and the end of said extension 20 of said lower wall 21 is bent downwardly in the form of a flange 38 over the lower edge of said outlet against the outside of said end wall 5 of the hand bag. The side wall 25 of the rear casing member 22 and the side wall 29 of the front casing member 21 terminate at 39 to form the upper edge of the discharge opening 36. The end of the front wall 24 of the front casing member 21, and the end of the rear wall 28 of the rear casing member 22, are extended through the outlet 30 37 in the end wall 5 of the hand bag, and said extensions of said walls are bent over the side edges of said outlet in the form of external flanges 40 and 41, resting and engaged against the outside of said end wall 5 of the hand bag. The extension of the walls 21, 24 and 28 of the casing 35 20 through the outlet 37 in the end wall 5 of the bag provide an unobstructed discharge opening 36 leading from the magazine 17 through said end wall of the bag and tie the casing to the bag 40 while holding the lower end of the casing members 21 and 22 together. A flap 42 is secured to the inside of the end wall 5 of the bag, as at 43, and normally extends below the upper edge of the outlet 37 in said end wall over the discharge 45 opening 36 in the casing 20, and closes said opening.

In the magazine 17 are placed cigarettes 43 or other articles to be dispensed, such as chewing gum, candy and the like, the lowermost article 50 resting upon the lower wall 21 of the front casing member 21 with its forward end in registration with the discharge opening 36 of the magazine, as illustrated in Figure 5 of the drawing. A follower 44 is mounted inside of the casing 55 cover 23 to be positioned in the magazine 17 above the articles 43 in the magazine, said follower comprising a follower plate 45, which bears upon the uppermost article 43, and a spring 46 secured at its lower ends to said plate, as at 47, and 60 at its upper end to the under side of the top wall of the casing cover 23, as at 48, which spring urges said follower plate against said uppermost article and holds the articles 43 compactly together in the magazine 17 and the lowermost article 65 against the lower wall 21 of the casing member 21 with sufficient friction to prevent said lowermost article from slipping out of the discharge opening 36.

The ejector 18 may comprise a single piece of 70 strip metal bent U-shape to form an ejecting head 50, and bent upwardly at one end in the form of a connecting member 51.

The ejector operating mechanism 19 comprises an operating stud shaft 52, an operating button 75 53 on said shaft, an arm 54 on said shaft, a sleeve

55 on the outer end of said arm, and a U-shaped spring member 56. The shaft 52 extends through the front wall 2 of the hand bag 1 and through the front wall 24 of the front casing member 21 into the casing compartment 34 for the ejector 5 operating mechanism, said shaft being journaled in said front wall 24 of said casing member. The button 53 is secured on the outer end of the operating shaft 52 adjacent the outside of the front wall 2 of the hand bag, the closing flap 7 of the hand bag being provided with a notch 57 to receive said button and permit turning thereof. The button 53 is ornamental and adds to the attractiveness of the hand bag. The arm 54 is secured on the inner end of the operating shaft 15 52 within the compartment 34. The U-shaped spring member 56 is fitted within the compartment 34 with its intermediate member 57 adjacent the upper horizontal flange 33 of the front casing member 21, and its arm members 58 and 20 59 bearing respectively against the vertical partition 32 and the end wall 26 of said front casing member. The lower end portion of the arm member 59 slidably extends through the sleeve 55 on the lower end of the arm 54 and the end of said 25 arm member is hooked through the upper end of the ejector connecting member 51, as at 60, and is thus pivotally connected to said connecting member.

The operation, uses and advantages of my invention are as follows:

Normally the button 53 and the flap 42 are in the position shown in Figure 1, and the mechanism and articles 43 within the dispenser 13 are in the position shown in Figure 5 of the drawing. 25

When it is desired to dispense a cigarette, the button 53 is grasped and turned clockwise, as illustrated in Figure 2 of the drawing, whereupon the shaft 52 and arm 54 are correspondingly turned, and the sleeve 55 engaging and sliding 40 upon the lower portion of the arm member 59 of the U-shaped spring member 56 swings the lower end of said arm member and the ejector 18 to the left. The ejector 18, on being thus moved toward the left, passes through the opening 33 below the 45 lower end of the partition 32, and the forward end or head 50 of the ejector engages the rear end of the lowermost cigarette 43 and partly ejects said cigarette from the magazine 17, the forward end portion of the cigarette passing out of the 50 magazine through the discharge opening 36 and raising the flap 42 above said discharge opening 55 to permit such ejection of the cigarette, as illustrated in Figure 2. The cigarette may then be grasped by its forward end and completely withdrawn from the magazine 17 through the discharge opening 36, whereupon the remaining cigarettes descend in the magazine 17 until the lowermost cigarette rests upon the bottom of the magazine in position to be ejected from the magazine, while the flap 42 drops over the discharge opening 36. Upon releasing the button 53, the dispenser mechanism shown in Figure 5 is returned to its normal position, as shown in said figure, by the spring action of the arm member 60 59, and said button is likewise returned to its normal position, as shown in Figure 1.

If for any reason, when a cigarette has been partly ejected from the bag by the ejecting mechanism, as illustrated in Figure 2, it is desired not 70 to withdraw said cigarette, said cigarette may be pushed back into the magazine 17 and the flap 42 allowed to drop over the discharge opening 36.

By means of my dispenser cigarettes may be carried in the hand bag within a small space and 75

without being crushed, and the cigarettes may be dispensed from the bag without opening the bag. Moreover, no tobacco will be left in the bag from the cigarettes.

5 When all of the cigarettes are dispensed from the magazine, the cover 23 and follower 45 may be removed from the casing 20 and the magazine recharged with fresh cigarettes.

It is obvious that various changes and modifications and variations may be made in practicing the invention in departure from the particular showing of the drawing and the description as given without, however, departing from the true spirit of the invention as defined by the scope of 15 the appended claims.

I claim:

1. A dispensing pocket-book comprising: a pocket-book structure having side and end walls; a container for a plurality of similar articles 20 mounted in said pocket-book structure; means for singly dispensing said articles from said container and through a normally concealed opening in a wall thereof; and an operating member for said means mounted exteriorly of the pocket-book 25 and forming an ornament for the pocket-book ostensibly unassociated with said means.

2. A dispensing pocket-book comprising: a pocket-book structure having accordion folded ends and side members projecting beyond said 30 ends; a container for a plurality of similar articles mounted in said pocket-book structure and having an outlet from the pocket-book at one of said ends; a flexible closure for said outlet normally

concealing the same; and means for singly dispensing said articles from said container through the outlet.

3. A dispensing pocket-book comprising: a pocket-book structure having accordion folded 5 ends and side members projecting beyond said ends; a container for a plurality of similar articles mounted in said pocket-book structure and having an outlet from the pocket-book at one of said ends; a flexible closure for said outlet normally 10 concealing the same and partially hidden by said side members; means for singly dispensing said articles from said container through the outlet; and an operating member for said means mounted exteriorly of the pocket-book and forming an 15 ornament for the pocket-book ostensibly unassociated with said means.

4. A dispensing pocket-book comprising: a pocket-book structure having side and end walls and a small opening through a wall thereof, a 20 container for a plurality of similar articles in said pocket-book structure having an opening in alignment with the aforesaid opening, means for connecting the pocket-book structure and container at the edges of said openings to mount the 25 container in the pocket-book structure, means in said container for singly dispensing said articles through the openings, and an operating member for said means mounted exteriorly of the pocket- 30 book and forming an ornament for the pocket-book ostensibly unassociated with said means.

BENJAMIN KASH.
